METHOD OF AND APPARATUS FOR CIR-
CULATING LIQUORS AND VAPORS IN DI-
GESTERSClark C. Heritage, Rumford, Maine, and Vance P.
Edwardes, New York, N. Y.

Application August 19, 1933, Serial No. 685,894

14 Claims. (Cl. 92—7)

This invention relates to a method of and apparatus for circulating liquids and vapors. More specifically this invention relates to a method of and apparatus for the circulation of cooking liquors in pulp digesters.

In the preparation of paper pulp by the direct sulphite cooking process as generally practiced, a pressure cooker or digester is loaded with wood chips and flooded with a cooking acid preferably introduced at the bottom of the digester. When sufficient acid has been introduced, the vessel is closed and the acid and chips are gradually brought to the proper temperature and pressure by forcing steam into the digester. The pressure and volume of liquid in the digester are regulated during the cooking or digesting by means of relief valves provided for the purpose.

By carrying out the process in this manner, it is not possible to obtain a uniform temperature throughout the digester and the yield and quality of the pulp produced varies greatly in different parts of the digester.

These objectionable features of the general cooking process may be overcome by thoroughly circulating and agitating the cooking liquor and vapors from the time that the acid is introduced into the digester.

We have now found that we can produce such circulation and agitation by means of gas or vapor lifts. According to our invention, we may use two distinct types of gas or vapor lifts. The one type, called an inside lift, causes circulation inside the digester and may be used during the heating up stage of the cooking process. The other type, called an outside lift, causes circulation to an outside vapor relief and liquid recovery system. This latter type may be brought into operation after the digester has been brought up to the proper temperature and pressure.

These vapor lifts comprise pipes or tubes mounted in the digester with their lower ends near the bottom of the digester. Inside each tube is a pipe of much smaller diameter having an open end terminating inside and slightly above the bottom of the tube through which a gas or vapor to actuate the lift may be introduced. The external tube of the inside lift terminates slightly above the liquid level in the digester and is preferably bent so that liquor and vapor emitted therefrom will be directed downwardly to the liquor in the digester. The upper ends of the external tubes of an outside lift do not terminate within the digester but are connected with the liquor recovery and vapor relief system located

outside the digester as will be hereinafter more fully described.

The gas or vapor lifts are caused to operate either by forcing the gas or vapor through the inside delivery pipe, allowing it to escape at the end of said pipe, or by releasing vapor in the external pipe at pressures below that maintained within the digester. The internal pipe is submerged in the liquor but terminates within the external pipe and when steam or other vapor is forced through the pipe, a vapor and liquor mixture is formed which rises in the external tube because this mixture is less dense than the solid column of liquor surrounding the tube. This operation is similar to the well-known air lift often used by the hydraulic engineer. The outside lifts, furthermore, may be actuated alone by maintaining the outside vapor relief system at a lower pressure than the pressure in the digester thereby causing a flow of liquor from the digester to an outside tank. Vapor is released from this tank and this vapor relief alone is sufficient to operate the outside lifts, as will be more fully hereinafter described.

It is, accordingly, an object of this invention to provide a process for circulating liquors in digesters by releasing a gas or vapor into a column of liquor in the digesters to reduce the specific gravity of the column by forming a gas or vapor-liquor mixture which rises through the column and is discharged either at the top or outside of the digester.

It is a further object of this invention to provide a process for circulating liquors and vapors in digesters by maintaining means without the digester at lower pressure than the pressure inside of the digester but at higher elevation whereby circulation is effected from the digester to the outside means due to their difference in pressure and whereby part of the liquor circulated may be returned to the digester by gravity if desired.

It is another object of this invention to provide apparatus for circulating liquid within a closed vessel for a period of time and then circulate part of the liquor to an outside system without the aid of moving mechanical elements such as fans, pumps and the like.

It is a further object of this invention to provide a system for circulating liquors and vapors in digesters by means of gas or vapor lifts whereby circulation is maintained inside the digester during the heating up stage by inside vapor lifts and after the digester is brought up to the proper

pressure and temperature changing the circulation to an outside vapor relief system.

It is a further object of this invention to provide an apparatus for circulating liquors and vapors, in digesters which includes liquid discharge tubes immersed in the liquid in the digester and means for releasing a gas or vapor into the discharge tube to cause the liquid to be discharged from said tube either at the top of the 10 digester or outside of the digester.

Other and further important objects of this invention will become apparent from the following description and appended claims.

Referring now to the drawing, which discloses 15 a preferred embodiment of our invention, the figure therein illustrated is a front elevation of a digester equipped with the circulating system of this invention, parts of the digester being broken away and the separator in the circulating 20 system being shown in section.

On the drawing:

The improved circulating system of this invention, indicated generally by the reference numeral 1, comprises a digester or pressure cooker 25 2 in the form of a reinforced sectional steel shell 3 having a domed top 4 and a conical bottom 5. The apex of the conical bottom 5 is provided with a flanged fitting 6 having flanges 7 and 9 for an acid line 10 and digester blow-off 12, respectively. 30 Acid line 10 and blow-off 12 are controlled by means of valves 13 and 15 provided in said elements.

The domed top 4 of the digester shell is provided with a flanged fitting 16 providing an opening by means of which the digester is charged with chips and to which is secured a plate 17 for normally closing the digester. The plate 17 is provided with a connection 18 for a pipe 19 so that the pressure in the digester operates a diaphragm valve 8 in a pipe line 71 supplying SO₂ and/or steam to the digester. The pressure of the vapor and other gases in the digester is indicated by the pressure gauge 20 mounted on the domed top 4.

45 The digester is supported in a vertical position by means of a plurality of standards or legs 21 secured to the conical bottom 5 by flanged brackets or lugs 22.

The domed top of the digester 2 is provided 50 with at least one flanged fitting or connection 23 forming a packing gland for a vertical discharge or delivery pipe 24 which projects through and into the digester at a point adjacent the base of the coned bottom 5. The lower or submerged end 55 of the delivery pipe 24 has connected thereto a strainer 25. Positioned concentrically in the delivery pipe 24 and extending substantially the entire length thereof is a pipe 26, the lower or submerged end 27 of which opens slightly above the 60 lower end of the outer pipe 24. The upper end 28 of pipe 26 is provided with a laterally extending section 29 which extends through packed outlets 30 in the delivery pipe 24 and fitting 23. The pipe section 29 is connected to a pressure operated 65 diaphragm valve 70 which valve is connected with a sulphur dioxide, sulphur dioxide and steam, or steam source 71.

The upper or outer end of the delivery pipe 24 is provided with coupling 32 by means of 70 which it is secured to a right angle pipe section 33 leading to an inlet 36 in the side wall of a pressure separator 37 arranged above the digester 2. Interposed in this pipe line 33 is a time controlled valve 34 the purpose of which will be more 75 fully hereinafter described.

A vertical discharge or delivery pipe 80 is mounted entirely within the digester 2 as shown. The lower end of the pipe 80 is provided with a strainer 81 similar to screen 25. The upper end of pipe 80, however, terminates within the digester above the level of the liquor and may be provided with an elbow section 82 to direct the liquor discharged through said pipe 80 downwardly toward the liquid level in the digester represented by dotted line S. The pipe 80 contains an inside pipe 83 which terminates at its lower end slightly above the lower end of pipe 80. Pipe 83 passes through the domed top 4 through a suitable packing to prevent leakage and is connected to a source of steam and sulphur dioxide 71 in a 10 similar manner to the pipe 26.

A pressure operated diaphragm valve 73 is located in the pipe line 83 between the top of the digester and the steam and sulphur dioxide source 71. A pressure relief valve 75 may be connected to the dome 4 of the digester by means of a pipe 76, on which pipe a pressure gauge 20 may also be mounted. A pipe 77 leads from the pressure relief valve 75 to the top of the diaphragm in valve 73 and also to the under side of the diaphragm in valve 70. Thus, when the valve 75, which is set at a given pressure, opens, the pressure is transmitted through pipe 77 to the top of the diaphragm in valve 73, thereby closing said valve 73, while at the same time the pressure is also transmitted to the under side of the diaphragm of valve 70 causing said valve to open. The steam and/or sulphur dioxide from pipe 71, instead of being directed into pipe 83, is thus directed into pipe 26 in the digester. This starts 30 the circulation to the outside vapor relief system through pipe 33 and sets a time valve 34 in operation.

The pressure separator 37 located above the digester 2 comprises a closed cylindrical container 38 having a tapered bottom 40 terminating in a flanged tubular outlet 41. The top of the separator is provided with a flange 42 upon which is secured a domed cover 43. The cover 43 is provided near the mid-part thereof with pressure indicating means 49. A T-fitting 46 is secured to the closure 43 and is provided with a pressure relief pipe 47 having an automatic pressure relief valve 48. The vertical branch of the T provides a support for the pressure gauge 49.

The flanged tubular outlet 41 of the pressure separator is provided with a closure 50 having a connection 51 for a pipe section 52 leading back to the digester as shown. A valve 63 in the pipe section 52 may be used to control the flow back to the digester. This valve, however, need not be used in normal operation.

A constant liquor level R is maintained by means of a float actuated liquor relief device 90 connected to the flanged tubular outlet 41 of the pressure separator 37 by means of a pipe section 91. The constant level device 90 contains a float actuated valve 92 which automatically opens when the liquid level is raised above R, allowing this liquor to discharge through pipe 94 either to an acid recovery system, or to the sewer.

A pipe line 64 having a valve 67 is provided in the side of the digester near the top for taking samples and also for emergency relieving liquor from the digester.

The piping arrangement of the circulating system described above may, of course, be varied from that disclosed without materially reducing the effectiveness of the system. For example, either inside or outside lifts may be used thru- 75

out the digestion. Furthermore, electrically operated valves or different types of pressure regulating valves than those indicated in the drawing may be used.

5 While only one outside lift and one inside lift have been described, it is obvious, of course, that additional inside and outside lifts may be used in the digester if desired.

In the operation of our device, wood chips are 10 introduced into the digester 2 through the opening in the fitting 16. The chips are then flooded with acid injected into the digester through the acid line 10 to a height indicated by the broken line S. At the same time the inside lift 80 is 15 brought into operation by introducing steam, sulphur dioxide or a mixture of sulphur dioxide and steam through pipe 71. The mixture of sulphur dioxide gas and steam may be obtained from another digester as vapor relief, from a central 20 evaporator handling both relief gas and liquor, from a steam actuated injector pulling vapor off of the outside separator of another digester or steam alone may be introduced from a boiler, since the lift may be operated by steam alone. 25 Circulation of liquor and vapors is thus maintained within the digester during the entire heating up stage so that the contents of the digester are always in a state of constant ebullition and so that uniformity of composition and of temperature throughout the digester is always maintained. During this stage of the operation, of course, valve 73 is open and valve 75 is closed. 30 The circulation is maintained, according to the principles of the well-known air lift, by forcing the sulphur dioxide and/or steam through the pipe 83 and releasing it at the bottom of the pipe 83 which terminates slightly above the bottom of the discharge pipe 80. The gases and liquor form a mixture which is less dense than the solid 35 column of liquid outside of the pipe 80. This mixture therefore raises in the pipe 80 and is discharged at 82 at the top of the digester.

When the digester reaches a predetermined temperature the vapor pressure of the contents 40 of the digester at this temperature, say 78 lbs., is sufficient to open the valve 75 to divert the flow from 83 to 26 or from the inside lift to the outside lift. This same action starts the time controlled valve 34 so that relief is begun to separator 37. 45 As the pressure continues to rise in the digester, the pressure regulating valve 8 comes into action and decreases or shuts off the supply of steam and/or SO₂ in pipe 71. This does not however stop the outside lift from functioning as the pressure difference between the digester and separator is sufficient to cause continuous release of vapor in the lift and the lift continues to function so long as this pressure difference exists. 50 This pressure difference continues to exist since the separator is constantly receiving vapor and liquor at a predetermined automatically controlled rate thru valve 34 and is maintained at a lower pressure than the digester by pressure relief valve 48 and the digester pressure is maintained by pressure regulating valve 8 controlling the admission of steam and/or SO₂.

The valve 8 in the supply line 71 may also be thermo-operated by the temperature in the discharge line 33. Thereby either the pressure within 55 the digester or the temperature of the discharge may regulate the feed.

A liquid level is maintained in the separator 37, as indicated at R on the drawing, so as to provide a height of liquor column sufficient to overcome 60 the differential pressure between the gas pres-

sure in the digester and in the separator and cause a continuous flow from the separator to the digester. In this way liquor constantly circulates from the digester into the separator by vapor lift action and from the separator back into the digester by gravity. The constant level device 90 removes the equivalent volume of steam and considerable vapor added thru the lifts and keeps the system from getting too full of liquid.

It is to be understood that the pressure in separator 37 may be so regulated that the circulation of the liquid from the digester can be effected without forcing sulphur dioxide or steam through pipe 26. Thus the flow of vapor and liquor from the digester to the separator can be entirely brought about due to the difference in pressure acting on the liquid column in pipe 24, partially by displacement and partially by vapor lift action.

It will be seen from the above that the inside lifts are brought into operation during the initial stages of the cooking process thereby causing a thorough circulation of vapor and liquors within the digester. When the cook has progressed to a certain predetermined point, the inside vapor lifts are thrown out of operation and the outside lifts are brought into operation automatically. The purpose of utilizing an outside lift during the latter stages of the cooking operation is to manipulate temperature pressure and liquor concentrations as may be required in the pulping process, water and SO₂ being constantly added and/or removed from the digester.

It will thus be appreciated that by constructing a device operating somewhat on the principle of an air lift, we are able to greatly improve the efficiency of pulp cooking processes by providing for a constant circulation of the cooking liquor in the pulp digesters.

While we have disclosed a preferred embodiment of our invention, it is to be understood that we do not propose to be limited thereto, as it is apparent that various details of construction may be varied without departing from the spirit of the invention disclosed.

We claim as our invention:

1. Apparatus for circulating liquid in pulp digesters, comprising in combination a pressure cooker having a liquid therein, a vertical pipe projecting into said cooker and having an open end submerged in the liquid therein, means for injecting a gas into the submerged end of said pipe to thereby decrease the effective density of the liquid in said pipe and cause it to flow therefrom, means for receiving said liquid and separating the gas therefrom, and means for returning the liquid to said cooker.

2. Apparatus for circulating liquid in pulp digesters, comprising in combination a pressure cooker having a liquid therein, a vertical delivery pipe projecting therein with a substantial part thereof submerged in the liquid in said digester, a gas pipe in said delivery pipe, means for forcing a gas therethrough and into said delivery pipe to thereby decrease the specific gravity of the liquid in said pipe and cause it to flow from said cooker, a receptacle for receiving said discharged liquid and separating the gas therefrom, and means for returning the liquid to said cooker.

3. Apparatus for circulating liquid in pulp digesters, comprising in combination a pressure cooker having a liquid therein, a vertical delivery pipe projecting into said cooker with a substantial portion submerged in the liquid therein, a gas pipe arranged in said delivery pipe,

- 5 a screen over the submerged end of said delivery pipe, means for forcing a gas under pressure through said gas pipe and into said delivery pipe to thereby reduce the density of the liquid in said pipe and cause it to flow from said cooker, a device connected to the outer end of said delivery pipe for receiving said discharged fluid and separating the gas contained therein, and a connection leading from said device to said cooker at a point above the liquid level therein to return the discharged liquid thereto.
- 10 4. The process of circulating cooking liquors in digesters, which comprises confining a column of the cooking liquor in the digester, releasing a gas into the column of liquor to decrease the effective specific gravity thereof whereby the column is discharged from the digester by the hydrostatic head of cooking liquor therein, collecting the discharged liquor and returning it to the digester.
- 15 5. The process of circulating cooking liquors in digesters, which comprises confining a column of the cooking liquor in the digester, forcing sulphur dioxide into said confined liquor column to decrease the effective density thereof whereby the column is discharged from the digester due to the hydrostatic head of the cooking liquor therein, collecting said discharged liquor, separating the entrained sulphur dioxide therefrom and returning the liquors to the digester.
- 20 6. The process of circulating cooking liquors in digesters, which comprises confining a column of liquid therein, injecting a stream of sulphur dioxide and steam into said column at the base thereof to decrease the effective density of the liquid column and thereby cause it to be discharged from the digester by the hydrostatic head of the cooking liquor in the digester, collecting the discharged liquor, separating the sulphur dioxide therefrom and returning the liquor to the digester.
- 25 7. Apparatus for circulating liquids in pulp digesters, comprising in combination, a pressure cooker having a liquid therein, a vertical pipe projecting into said cooker having an open end submerged in the liquor therein, the upper end of said vertical pipe being connected to a tank wherein vapors and the liquid rising in the pipe are separated, a relief valve on said tank to maintain pressure therein lower than the pressure in the digester, a liquid return pipe from said tank to the digester and float operated means to remove part of the liquid from circulation.
- 30 8. The process of circulating cooking liquors in digesters which comprises confining a column of the cooking liquor in the digester having an open end near the bottom thereof and an upper end connected with an outside tank maintained at a lower pressure than said digester whereby liquid and vapors are caused to flow from the digester to the tank due to vapor lift and the decrease in pressure, separating the liquid from the vapors in said tank and returning part or all of the liquid to the digester.
- 35 9. A device for circulating liquid and vapors in digesters, comprising in combination with a digester, means mounted in said digester partially submerged in and opening into the liquid therein, means for forcing gas into said first means near the submerged end to thereby decrease the specific gravity of the liquid in said first means and cause it to flow together with said gas toward the top of said digester to be there discharged, means similar to said first means for directing said gaseous liquid mixture from said digester to an outside receiver and means for returning part of the liquid from said receiver to said digester.
- 40 10. The process of circulating liquid and vapors in a digester which comprises confining a plurality of columns of the liquid in the digester, flowing the liquid through said columns from the bottom to the top thereof, regulating the flow through the said columns by the pressure within the digester and discharging some of the liquid from the digester for a predetermined period to prevent flooding.
- 45 11. Apparatus for circulating liquids and vapors in digesters which comprises a pressure cooker having a liquid therein, a plurality of vertical pipes projecting into said cooker and having open ends submerged in the liquor therein, means for releasing a gas or vapor in the submerged ends of said pipes to decrease the specific gravity of the liquid confined therein and cause the liquid to flow toward the top of the digester, means controlled by the pressure within the digester to regulate the releasing of gases or vapors in the respective pipes, a receptacle for receiving some of the liquid from said pipes and separating the gas or vapors therefrom and means for returning the liquid to said cooker.
- 50 12. In an apparatus of the class described, in combination, a pressure cooker, an outside receptacle in communication therewith, a vertical column in said cooker having an open end near the bottom of the cooker and an open top near the top of the cooker, a second vertical column in said cooker having an open end near the bottom thereof, a pipe connecting the top of said second column with said receptacle, means for releasing a gas or vapor in said columns near the bottoms thereof to lift the confined liquid in the columns, means controlled by the pressure within the cooker for operating the release means and automatically controlled means for regulating the flow of the lifted liquid from the second column to the receptacle.
- 55 13. In an apparatus of the class described in combination, a pulp digester, a vapor and liquid separator in communication therewith, an inside vapor lift inside the digester, a second vapor lift in said digester communicating with the separator, a valve controlled by pressure within the digester for regulating the amount of vapor fed to said vapor lifts, automatically controlled means for regulating the discharge from the second vapor lift to the separator and means for returning part of the liquid in the separator to the digester.
- 60 14. The process of circulating liquid and vapors in pulp digesters which comprises confining a column of the liquor in the digester, flowing the liquor in said column from the bottom to the top thereof, confining a second column of the liquor in said digester, flowing the liquor in said second column to an outside receptacle for a predetermined period, separating gases or vapor from the liquid flowed into said receptacle, and returning part of the liquid to the digester.
